[57] CLAIM

The ornamental design for a microwave tea kettle, as shown and described.

DESCRIPTION

FIG. 1 is a front elevational view of a microwave tea kettle showing my new design with the rear elevational view not shown, being a mirror image thereof;

FIG. 2 is a left side elevation thereof;

FIG. 3 is a right side elevation thereof;

FIG. 4 is a top plan view thereof; and

FIG. 5 is a bottom plan view thereof.
